[57] CLAIM

The ornamental design for an optical receiver/transmitter module, as shown.

DESCRIPTION

FIG. 1 is a perspective view from the front, top and right side of an optical receiver/transmitter module showing my new design;

FIG. 2 is a perspective view from the rear, top and left side thereof;

FIG. 3 is a front elevational view thereof;

FIG. 4 is a rear elevational view thereof;

FIG. 5 is a right side elevational view thereof;

FIG. 6 is a top plan view thereof; and,

FIG. 7 is a bottom plan view thereof.

FIG. 1

FIG. 2

FIG. 3

FIG. 4

FIG. 5

FIG. 6

FIG. 7
